SLIDE PROJECTOR

Kenneth D. Maier, Mendon, N.Y., assignor to Bausch & Lomb Optical Company, Rochester, N.Y., a corporation of New York

Filed Nov. 12, 1959, Ser. No. 58,308

Term of patent 14 years

(Cl. D61—1)

FIG. 1

FIG. 2

Fig. 1 is a front perspective view of a slide projector showing my new design; and

Fig. 2 is a rear perspective view thereof.

The dominant features of my new design are shown in solid lines in the drawing. The broken line fragmentary showing of a slide tray in Fig. 2 is for illustrative purposes only.

I claim:

The ornamental design for a slide projector, substantially as shown and described.
